UNITED STATES PATENT OFFICE.

ARTEMAS ROBERTS, OF NORMAL, NEBRASKA.

STEEL SQUARE.

SPECIFICATION forming part of Letters Patent No. 651,057, dated June 5, 1900.

Application filed November 18, 1899. Serial No. 737,417. (No model.)

To all whom it may concern:

Be it known that I, ARTEMAS ROBERTS, a citizen of the United States, residing at Normal, in the county of Lancaster and State of 5 Nebraska, have invented new and useful Improvements in Steel Squares, of which the following is a specification.

My invention relates to certain improvements in carpenters' steel squares, the improvements contemplated being, first, the substitution upon the blade of the steel square in place of certain figures or tables usually placed thereon of a conveniently-arranged rafter-table giving in duodecimals or feet, 15 inches, and twelfths of an inch the length of rafters having a certain defined pitch or inclination and a given horizontal run, and, second, to give in connection with the rafter-table the figures for the lengths, which, taken 20 on the blade and tongue of the square, will give the bevels for the horizontal and vertical cuts for rafters having the given pitch or inclination. I accomplish these objects in the manner illustrated in the accompanying 25 drawing, which is a view of a portion of the blade of a carpenter's steel square, showing the arrangement of my improved rafter-table with the figures giving the horizontal and vertical cuts for each pitch, as is more fully 30 described below.

Upon the blade A A of a carpenter's steel square, made in the usual form, and the place usually occupied by a lumber-table I place a rafter table B B. This table consists of a 35 number of parallel rulings having at the left end figures C, indicating a certain pitch of inclination, while along between the rulings and opposite the usual figures denoting the inches on the outside of the square are given 40 the lengths in duodecimals or feet, inches, and twelfths of an inch of rafters having the run in either feet or inches indicated by said figures and of the given pitch or inclination. In case the run of the rafters is taken in feet 45 we call one inch on the square a "foot," and the readings of the table will give the lengths correctly. In case the run is taken in inches the readings of the table will be in inches, twelfths, and one hundred and forty-fourths 50 of an inch, and the latter may be neglected in most cases. If the given run consists of feet and inches, the length of the rafter may be taken for the given number of feet and

for the given number of inches, and the two added together will give the entire length. 55

To illustrate: Suppose the run of a rafter to be twenty-one feet and five inches (21' 5") and the roof to have one-fourth ($\frac{1}{4}$) pitch. In the column indicating pitches we find one-fourth, ($\frac{1}{4}$), and following the ruling we find 60 under the figures "21" on the outside of the square the length of a rafter having a run of twenty-one feet, (21'), which is twenty-three feet five inches and nine-twelfths of an inch, and under the figure "5" we find the length 65 five inches and seven-twelfths of an inch of a rafter of five inches run, and adding these we get the whole length of the rafter, which is twenty-nine feet no inches and ten-twelfths of an inch, (29' 0" 10"). In formulating 70 this table I have adhered to the method in common use among carpenters of calling the proportion between the vertical height of the roof and the width of the building or double the run of the rafter the "pitch" of the rafter. 75 At the right of this table and opposite each of the ruled lines I place the figures, which, taken upon the blade and tongue of the square, give the bevels for the horizontal and vertical cuts of rafters having the designated 80 pitch or inclination.

Having thus fully described my invention, what I claim is—

1. A carpenter's steel square made in the usual form and having upon one side of the 85 blade a table giving the lengths in duodecimals, or feet, inches and twelfths of an inch, of rafters having a certain defined pitch or inclination and a given horizontal run, the latter being indicated by the usual figures 90 which indicate inches on the square substantially as described.

2. In combination with a carpenter's steel square of the usual form a rafter-table, made as shown and described, in which the runs of 95 rafters are indicated by the usual figures denoting inches on the square, while the rafter lengths are given in feet, inches and twelfths, and having in connection therewith figures which taken upon the blade and tongue of the 100 square will give the bevels for the horizontal and vertical cuts, substantially as set forth.

ARTEMAS ROBERTS.
